ELASTIC BIT BREAKER

John A. Zublin, Los Angeles, Calif.

Application June 26, 1939, Serial No. 281,104

4 Claims. (Cl. 255—1)

This invention relates to the drilling of wells, more particularly, to rotary drilling.

Modern drilling is accomplished by a bit fastened to a drill collar, the collar suspended from a string of drill pipe which extends to the surface. Changing the bit, necessitated by the wear thereon incident to use, is accomplished by raising the drill pipe and drill collar to above the rotary table, and securing the bit to the table 10 against rotation with respect to the table, and using tongs upon the drill collar, to break or tighten the joint between the collar and the bit. When the collar is loose enough to turn, it is spun by a rope or the rotary table turned to 15 drive the bit about.

When the drill collar is first placed over the bit, it is lowered by letting down the elevators, and the weight of the drill collar allowed to rest upon the pin of the bit, after which the bit and 20 collar are rotated with respect to each other until the joint is set up. In this lowering, extreme care is necessary on the part of the driller to ensure that the collar does not come down upon the bit too hard, for the bit is rigidly supported and the mass of the collar so great that the threads of the joint would be subject to de- 25 forming stresses if the collar were to engage them at any speed.

The hook holding the elevator has a spring in 30 it, for the purpose of lifting the stands of drill pipe as they disengage on breaking the tool joints, and to permit easy assembly of drill pipe in the trip into the hole, but such spring is ineffective in action upon the drill collars, as the collars are 35 so heavy that the spring, designed for stands of drill pipe, is ineffective, the load being taken without springing when it is much greater than the weight of a stand of pipe.

Much damage to threads results from the collar hitting the threads of the pin eccentrically, either the outside surface of the collar or the interior of the threaded box. The ordinary breaker supports the bit more or less rigidly, the teeth of the bit biting into the metal of the bottom of the breaker and preventing the bit from 45 moving radially when the pin is subject to radial impacts. Further, the cutter teeth of the bit are not intended to withstand impact loads as the collar engages the bit, and are therefore sometimes broken while making up the bit on the drill collar.

It therefore becomes a primary object of my invention to protect the threads of the bit and drill collar as the collar is engaged with the 50 bit.

It is a further object of my invention to provide means for the protection of the teeth of the bit cutter as it is placed in the breaker and as the collar is stabbed onto the bit.

It is a further object of my invention to provide means for permitting the threads to engage as the bit and collar are rotated relatively to each other, which will ensure movement of the bit 5 sufficiently to engage the threads.

Briefly, what I propose to do is to provide a 10 breaker with a cushioning element, to engage the bottom of the bit, and of sufficient resiliency to give under the combined weights of the bit and collar, and force the bit upwardly into the collar when the collar in turning reaches the proper 15 position for engagement of the threads.

I further intend to provide sufficient resiliency radially of the bit pin to permit it to give under impact loads sideways of the pin.

In the drawing:

Figure 1 is a general view of my improved breaker in use, partly in section; and

Figure 2 is a perspective view of the top of my improved breaker.

Referring to the drawing, the bit breaker 10 25 is of a generally basket shaped configuration, with a top 11 to fit the square recess in the rotary table which normally holds the kelly bushing. The top of the breaker is provided with an opening 13, of such a shape as to permit entry 30 of the bit, but to prevent rotation of the bit in the breaker.

Fastened below the top 11 is the receptacle 14, generally tapered, in usual practice, to clear the tapered opening in the rotary which takes the 35 slips.

Mounted in the receptacle is a cushioning element 12, of rubber, for example, or a spring assembly, or any other suitable cushioning means 40 for engaging the bit as it is lowered into the breaker. This cushioning element is capable of horizontal as well as vertical movement, so that under influence of eccentric loads, or impacts on the sides of the pin of the bit, the bit will pivot about the edge of the opening 13 to cushion the 45 blow, and not offer a rigid resistance to impact, tending to damage the threads, and, incidentally, protecting the teeth of the cutters from damage tending to split off the hard facing of the teeth.

In Figure 1 I have illustrated my breaker in 50 operation. The breaker fits in the opening in the rotary, with the top engaging the square hole 15 which takes the kelly bushing, and the basket clears the tapered portion 16 provided for the slips. The bit 17 is placed therein, and the 55

collar 18 lowered by the hook 19 and the elevator 20 into engagement, as is the usual practice. However, instead of depending upon the spring (not shown) usually present within the swivel 5 mechanism of the hook, to protect the threads as the collar engages them, and to force the threads into engagement, the cushion 12 is used to perform these functions. This change makes it possible for the driller to assemble the bit 10 and collar more readily, as he can lower the collar until the joint engages, much more rapidly than would be safe if the bit were solidly supported. The cushion then supports some of the weight of the collar, and the bit sinks into 15 the cushion. Upon relative rotation of the bit and collar, either by turning the table or by spinning the collar, the threads will come to the proper position to engage, and the bit will snap upwards, and continued rotation will screw the 20 bit onto the collar. Inasmuch as there is no movement of the heavy drill collar in an axial direction which is necessary for the engagement of the threads, not only is the impact of the collar threads on the bit threads minimized when 25 the collar is lowered over the bit, but also there is no heavy load imposed when the bit snaps up when the threads are in proper angular relation for screwing together.

In view of the fact that the cushion is never 30 called upon to support more than an impact load of the drill collar on the bit, it can be made quite soft, comparatively speaking. Since the bit is of considerably lower mass than the drill collar, the mass of the drill collar is ineffective 35 in damaging the threads upon impact, which also saves the threads.

It is to be understood that the shown form is not limitative, but illustrative only. The cushion shown need not be in the basket, but could 40 be between the breaker and the table, or the breaker itself could be elastic. But the form shown is the simplest, and it protects the teeth of the cutters, which, in the case of teeth intended to dig soft, abrasive material, are com- 45 paratively delicate and lose their efficiency if damaged.

Having described my invention, I claim:

1. In a breaker for drill bits, a plate with outside edges adapted to engage the rotary table and prevent rotation of the plate with respect to the table, an opening in the plate adapted to receive a bit and prevent rotation of the bit with respect to the plate, a resilient pad mounted under the plate adapted to engage the bottom of said bit and hold it upright in cooperation with the opening of the plate, said pad being vertically and horizontally resilient, whereby the bit can move axially and pivot along a transverse axis under influence of the weight of and impacts by the drill collar. 5

2. A support for a bit to be used in attaching the bit to a drill collar including a basket shaped member, means preventing rotation of said member with respect to a table, means supporting said member with respect to the table, a resilient bottom in said basket for supporting the bit, and rigid means above the bottom of the basket engaging the sides of the bit to prevent lateral displacement of the bit at that point, whereby said bit is resiliently supported in an upright position for engagement with the drill collar. 10

3. A support for a bit to be used in attaching the bit to a drill collar, including a portion adapted to engage a rotary table, a portion adapted to engage the bit, both of said portions cooperating to prevent rotation of the bit with respect to the table, and resilient means engaging the bottom of the bit, said last mentioned means being resilient under the weight of a drill collar. 25

4. A support for a bit to be used in attaching the bit to a drill collar, including a portion adapted to engage a rotary table, a portion adapted to engage the bit, both of said portions cooperating to prevent rotation of the bit with respect to the table, and resilient means engaging the cutting edges of the bit, said last mentioned means being resilient under the weight of a drill collar. 30
